UNITED STATES PATENT OFFICE.

FRITZ GOLDBACH, OF DEAD MOOSE LAKE, SASKATCHEWAN, CANADA.

GAME OF SKILL.

Application filed June 20, 1923. Serial No. 646,599.

To all whom it may concern:

Be it known that I, FRITZ GOLDBACH, a citizen of Canada, residing at Dead Moose Lake, in the Province of Saskatchewan and 5 Dominion of Canada, have invented certain new and useful Improvements in Games of Skill, of which the following is a specification.

My invention relates to a game that can be 10 played by any number of players, and the main object of the invention is to construct the device so that a great amount of skill will have to be used for successfully playing the game.

15 The device is built in the form of a stand, preferably representing some animal and is furnished with a track or guide, upon which a ball or any other small object is made to run actuated by the swinging of the arms of 20 the figure. The arms are actuated by the manipulation of the treadles representing feet and the track is interrupted about its middle. The object is to press the treadles down sufficiently to make the ball barely 25 reach the gap in the track and leave the same. If too great a force is used the ball will pass over the gap and down the other side of the track, but if too little force is used, the ball will return to the hand that 30 threw it.

The device may also be built with an uninterrupted track, in which case the ball will pass from end to end thereof, imitating the throwing of a ball over the head of the figure 35 and back again. In this case, the device is more of the character of a toy and the treadles may then be operated by a revolving shaft either by hand or by motor.

In the accompanying drawings, two em- 40 bodiments of the invention have been illustrated; and—

Figure 1 is a perspective view of the device showing the preferred form of the invention with an interrupted track;

45 Figure 2 is a vertical section along line 2—2 of Figure 1;

Figure 3 is a vertical section along line 3—3 of Figure 2;

50 Figure 4 is a similar view to Figure 3 representing a modified form of the invention; and

Figure 5 is a fragmentary vertical section along line 5—5 of Figure 4.

In the drawings, reference numeral 10 55 represents a stand provided with a chamber 11 extending through the greater part of the

stand and intended to house the mechanical movement of the device. In this case, the stand represents a bear standing on his hind legs and provided with front legs or arms 12 hinged on spindles 13 in the body or stand 10. The arms 12 project through side slits 14 in the stand so as to be able to swing up and down around the spindle 13. The arms have short inwardly projecting levers 14, each carrying a pivot pin 15, upon which is suspended a connecting rod 16 reaching downwardly in the chamber 11 and connecting with the treadles or feet 17 at about a central point thereof. These feet 17 are 65 pivoted on other spindles 18 on the stand, as best seen in Figure 2. It will accordingly be possible to raise each arm independently by pressing down the corresponding foot or treadle 17 when a pull is communicated 70 through the link 16 and lever 14 to the arm 12.

A piece of wire 19 is securely mounted in the stand 10 and provides a circular guide or track for a small ball 20 or any other object 80 such as a bottle or disk which has an aperture engaging over the wire or track 19. At 21 an interruption or gap is formed on the wire, of a width slightly more than the diameter of the ball 20 so that the ball may fall 85 down from the track when reaching this gap. The arms 12 are preferably furnished with fingers 23 engaging on both sides of the track 19 in order not to leave the track when they are swung and to make sure engagement with the ball 20.

At the top of the head of the bear or stand 10 is formed a pocket 24 directly under the gap 21 and intended to catch a falling ball. This pocket terminates with 95 a passage 25 opening downwardly into the mouth of the figure, and over the nose of the same is preferably hung a basket or other receptacle 26, into which the ball, coming from the pocket 24 and running 100 through the passage 25, will fall.

In playing this game, the players depress alternately, the treadles or feet 17 of the figure, when the corresponding arm 12 will 105 will be swung upwardly along the track 19 into its extreme upward position, indicated by dotted lines in Figure 1, as at 27. The player's aim is to exert just enough pressure upon the treadle to throw the ball upwards along the track 19 so that the ball 110 reaches the gap 21 and does not have inertia to pass from one end of the wire

to the other at the gap, but will fall down into the pocket 24 and be delivered into the basket 26. If too much pressure is used, the ball will pass the gap and fall down 5 along the other half of the track 19 until stopped by the arm on that side of the figure. If too little force is used, the ball will not reach the gap 21, but return to the arm 12 that threw it. For each ball that 10 is collected in the basket 26, a point is counted, and the game is to get the greatest number of balls into the basket with as few depressions of the treadles 17 as possible.

15 In order to be able to count the strokes or depressions of the treadles 17, a siren actuated by an air bag 28 compressed by the treadle 17, may be furnished at the bottom of the stand.

20 Referring, now, particularly to Figures 4 and 5 where a stand 30, similar to the one already described, is indicated, this stand has, however, a closed track 31 of a circular wire secured as at 32 in the stand. The 25 arms 33 are here pivoted on the spindles 34 as already described and the fingers 35 engage the track, upon which the ball 36 is intended to travel. The arms 33 have inward extensions 37 carrying pins 38 for 30 links 39 which, however, in this case extend through the bottom 40 of the stand into a small box or pedestal 41, upon which the stand is mounted. The ends of the stand 35 carry abutment members or fixed 35 treadles 42, and in front of these abutments is mounted a revoluble shaft 43 carried in suitable bearings in the box 41. On this shaft are secured wings or vanes 44 situated in the path of the abutments 42 so that when 40 the shaft 43 is revolved, the wings 44 will alternately contact and depress the abutments 42 on the right and left links 39. The shaft 43 carries on the outside of the box, 45 an operating handle 45 and this may be arranged to be turned by any suitable motor instead of by hand. When the device is constructed as a toy, as shown in Figures 4 and 5, the pocket 24 and passage 25, in the head of the figure will, of course, not be needed and the head may be preferably made solid instead.

50 In this form of the device, the latter constitutes a plaything so that when the shaft 43 is turned, the arms 33 alternate in moving upwards, and the ball 36 is thrown around the track 31 from one arm to the other as long as the shaft 43 is revolved.

55 It is evident that this device may be built in different sizes. For instance, a small 60 size suitable to place on the table could be operated by the player's fingers, while a somewhat larger stand may require the use of the player's whole hand. A full size stand representing a full grown bear, may 65 also be constructed in accordance with the

subject matter of this invention, to be erected on the ground and to be operated by the player's foot. In this case, of course, the ball or object to be thrown from hand to hand would be constructed larger and 70 heavier so that a great deal of force would have to be exerted to raise the ball and throw it over the top of the figure's head. In the latter case, the device may be constructed of metal or wood, but for the 75 smaller sizes, celluloid, papier-mâché, or any other suitable material may be used.

It is not necessary to have the throw about 90°, as indicated in Figure 1, but the arms might be started from horizontal position to about 45° upwards, particularly for the larger size figures, and for the device constructed as a game with the interrupted track.

Having thus described the invention, 85 what is claimed as new is:

1. A toy comprising a stand, arms pivoted in the stand, an arcuate track on the stand, elements on the extreme ends of said arms slidably engaging said track, a movable 90 member associated with said track and held by gravity in contact with the arms, and means for actuating said arms to start said member along said track.

2. A toy comprising a stand, arms pivoted 95 in the stand, an arcuate track on the stand, elements on the extreme ends of said arms slidably engaging said track, a movable member associated with said track and held by gravity in contact with the arms, and 100 means for actuating said arms to start said member along said track, said track having a gap at a substantially medial point permitting said member to leave the guide.

3. A game of skill comprising a stand, 105 arms pivoted in the stand, an arcuate track on the stand, elements on the extreme ends of said arms slidably engaging said track, a movable member associated with said track and held by gravity in contact with the 110 arms, means for actuating said arms to start said member along said track, said track having a gap at a substantially medial point permitting said member to leave the track, 115 and said stand being provided with a pocket in juxtaposition with said gap.

4. A game of skill comprising a stand, arms pivoted in the stand, an arcuate track on the stand, elements on the extreme ends of said arms slidably engaging said track, a 120 movable member associated with said track and held by gravity in contact with the arms, and means for actuating said arms to start said member along said track, said 125 means including treadles pivoted on said stand and positive connections between said arms and said treadles.

5. A game of skill comprising a stand, arms pivoted in the stand, an arcuate track 130 on the stand, elements on the extreme ends

- of said arms slidably engaging said track, a movable member associated with said track and held by gravity in contact with the arms, means for actuating said arms to start said member along said track, said track having a gap at a substantially medial point permitting said member to leave the track, and said means including treadles pivoted on said stand and positive connections between said arms and said treadles. 5
6. A game of skill comprising a stand, arms pivoted in the stand, an arcuate track on the stand, elements on the extreme ends of said arms slidably engaging said track, a movable member associated with said track and held by gravity in contact with the arms, means for actuating said arms to start said member along said track, said track having a gap at a substantially medial point permitting said member to leave the track, said stand being provided with a pocket in juxtaposition with said gap, and said means including treadles pivoted on said stand and positive connections between said arms and said treadles. 10
- 15
7. A game of skill comprising a stand, arms pivoted in the stand, an arcuate track on the stand, elements on the extreme ends of said arms slidably engaging said track, a movable member associated with said track and held by gravity in contact with the arms, and means for actuating said arms to start said member along said track, said means including treadles and positive connections between said treadles and said arms. 20
- 25
8. A toy comprising a stand, arms pivoted in the stand, an arcuate track on the stand, elements on the extreme ends of said arms slidably engaging said track, a movable member associated with said track and held by gravity in contact with the arms, means for actuating said arms to start said member along said track, said means including treadles and positive connections between said treadles and said arms. 30
- 35
- member associated with said track and held by gravity in contact with the arms, means for actuating said arms to start said member along said track, said means including treadles and positive connections between said treadles and said arms, a shaft revolvably mounted in said stand, and radial fingers on said shaft adapted to register with said treadles to move the same. 40
- 45
9. A game of skill comprising a stand, arms pivoted in the stand, an arcuate track on the stand, elements on the extreme ends of said arms slidably engaging said track, a movable member associated with said track and held by gravity in contact with the arms, means for actuating said arms to start said member along said track, said means including treadles pivoted on said stand and positive connections between said arms and said treadles, a siren, and an air bag for the siren mounted in said stand in juxtaposition to said treadles and adapted to be actuated by the movement of said treadles. 50
- 55
10. A game of skill comprising a stand, arms pivoted in the stand, an arcuate track on the stand, elements on the extreme ends of said arms slidably engaging said track, a movable member associated with said track and held by gravity in contact with the arms, means for actuating said arms to start said member along said track, said means including treadles and positive connections between said treadles and said arms, a siren, and an air bag for the siren mounted in said stand in juxtaposition to said treadles and adapted to be actuated by the movement of said treadles. 60
- 65
- 70
- 75

In testimony whereof I affix my signature.
FRITZ GOLDBACH. [L. S.]
